BOBBIN-THREAD TENSION THREADING
DEVICE FOR SEWING MACHINESHenry C. Nissen, Stratford, Conn., assignor to
The Singer Manufacturing Company, Elizabeth,
N.J., a corporation of New Jersey

Application October 19, 1939, Serial No. 300,098

6 Claims. (Cl. 112—233)

This invention relates to lock-stitch sewing machines and more particularly to lock-stitch sewing machines having a work-supporting arm or horn closely embracing a loop-taker which functions to cast needle-thread-loops about an under-thread mass.

In a commercially well known class of lock-stitch sewing machines, the under-thread mass is wound upon a bobbin removably disposed in 10 a cavity of a bobbin-carrier journaled in the race-way of a loop-taker which is of the horizontal-axis rotary hook type. The bobbin-carrier is peripherally provided with a tension-spring for 15 tensioning the thread leading from the bobbin to the needle-aperture in the work-support. As the bobbin-carrier is directly journaled in the loop-taker, the bobbin alone is removed from the loop-taker when replenishing the under-thread supply and the bobbin-thread therefore has to be 20 drawn under the thread-carrier tension-spring in the operative position of the thread-carrier in the loop-taker.

In flat-bed sewing machines or even in sewing machines having comparatively large work-arms, 25 there is sufficient space between the loop-taker and the adjacent wall of the bed-plate or work-arm to permit of drawing the bobbin-thread under the tension-spring of the bobbin-carrier. However, when the work-arm which houses the 30 loop-taker is of small compass so as barely to clear said loop-taker, difficulty has been experienced in drawing the bobbin-thread under its tension-spring.

It is an object of the present invention to provide 35 means for conveniently replenishing the under-thread supply of a sewing machine loop-taker which is contiguous to a frame-wall of the sewing machine.

A further object of the invention is to provide 40 means insuring a free bobbin-thread end after replenishment of the bobbin-thread in a lock-stitch sewing machine having a work-arm including a removable or openable end-closure member.

45 Other and more specific objects of the invention will be apparent from the following description taken in connection with the accompanying drawing which illustrates a preferred embodiment of the invention, and in which:

50 Fig. 1 represents a perspective view of the free end portion of the work-arm of a darning machine, together with the lower end portions of the needle-bar and presser-bar, the work-arm end-closure plate and the bobbin-latch of the bobbin-carrier being both open, as when replen-

ishing a bobbin. Fig. 2 is a view in front elevation of the end portion of the same work-arm. Figs. 3 and 4, respectively, represent perspective views of the bobbin-carrier and the loop-taker. Fig. 5 is an enlarged front side elevation of the bobbin-carrier. Fig. 6 represents an enlarged section of the bobbin-carrier, substantially on the line 6—6, of Fig. 5. Fig. 7 is an enlarged sectional view of the bobbin-carrier on the line 7—7 of Fig. 6.

The sewing machine in part shown in the drawing has a cylindrical work-arm 1 upon the free end portion of which is detachably secured, by a screw 2, a correspondingly shaped end-cap 3 provided with a needle-aperture 4. The end-cap 3 has an irregular flange 5 partly closing but leaving bobbin-removal clearance at the free end of the work-arm. Pivotedly secured to the lower portion of the end-cap flange 5, by a screw 6, is an end-closure plate 7 provided with a nub 8 adapted to enter an aperture 9 in the flange 5, thereby to hold the end-closure plate releasably in work-arm closing position.

Housed by the end-cap 3 of the work-arm is a rotary loop-taker 10 of well known construction, having a cup-shaped body provided with a needle-thread loop-seizing beak 11 and an internal bobbin-carrier raceway 12. The loop-taker 10 is carried by a rotary loop-taker shaft 13 journaled horizontally in the work-arm 1 to extend lengthwise thereof. The rim of the loop-taker 10 is disposed closely adjacent the end-closure plate 7 of the end-cap 3, which latter is of small compass and closely embraces the loop-taker, whereby endless work of small size may be placed upon the work-arm.

The cup-shaped bobbin-carrier 14 has a peripheral bearing-rib 15 journaled in the raceway 12 of the loop-taker, being retained in said raceway by a gib 16 detachably secured to the loop-taker. The bobbin-carrier 14 also has a flange 17 at its rim, said flange being formed with a stop-notch 18 entered by a stop-finger 19 projecting inwardly from the end-cap flange 5, whereby the bobbin-carrier is restrained against rotation with the loop-taker. A bobbin 20 is housed by the bobbin-carrier 14 and is rotatable upon the usual bobbin-carrier post 21, upon which latter is pivotally mounted a bobbin-retaining latch 22. In its closed position, the free 50 end of the latch 22 is disposed in a notch 23 in the bobbin-carrier flange 17.

The front side wall 14' of the bobbin-carrier 14 is partly cut away to provide an inverted V-shaped thread-slot 24 open to the flange-notch 23. 55

Bearing yieldingly upon the bobbin-carrier side wall 14', adjacent to the rounded apex of the thread-slot 24, is a bobbin-thread tension-spring 25 partly underlying the flange 17 and secured 5 upon the side wall 14' of the bobbin-carrier by a screw 26, said spring being adjusted as to tension by a screw 27. The inwardly bent free end of the tension-spring 25 has a thread-guiding notch 28 overlying a clearance-recess 30 in the bobbin-carrier side wall 14'.

After a wound bobbin 20 has been inserted in the bobbin-carrier, upon the post 21 thereof, the end of the bobbin-thread is passed outwardly through the flange-notch 28 and preferably before 15 the latch 22 is closed. To complete the threading of the bobbin-carrier, the bobbin-thread is then passed under the tension-spring 25 by drawing the thread upwardly and laterally into the notch 28 in the free end of said spring.

While the described loop-taker and bobbin-carrier are well known in the art, the employment thereof in a machine having a work-arm of small compass and housing the loop-taker, or having some other analogous frame-structure, 20 renders it difficult to complete the threading of the bobbin-carrier. To obviate this difficulty, the front wall of the work-arm end-cap 3 is partly cut away to provide a curved clearance recess 30 in the outer end of said cap and adjacent to the bobbin-carrier tension-spring 25, the edge of the cut-away end-cap flange 5 preferably merging into the cut-away edge of the end-cap defining the recess 30. Extending upwardly in the front wall of the end-cap 3 from the recess 30 therein and in a direction slightly inclined away from the free end of the work-arm is a thread-guiding and detaining slit 31 terminating at its upper end in advance of the needle-aperture 4. The thread-guiding slit 31 is so disposed with respect to the bobbin-carrier 14 that when the bobbin-thread leading outwardly through the bobbin-carrier notch 28 is drawn upwardly in the slit 31, said thread is at the same time drawn under the tension-spring 25 and into the thread-guiding notch 28 of said spring.

By extending the thread-guiding slit 31 upwardly from the clearance-recess 30, the bobbin-thread may be readily passed into the lower open end of said slit by merely drawing the thread 50 along the edge of the end-cap flange 5, which edge continues into the clearance-recess 30. The bobbin-thread drawn into the thread-guiding slit 31 is loosely detained thereby until the end of the bobbin-thread is pulled out of said slit by 55 the drawing up of the first needle-thread loop presented to the loop-taker 16 by the usual needle 32 carried by the vertically reciprocatory needle-bar 33. Consequently, the bobbin-thread is held away from the open end of the end-cap 60 3 and is therefore not pinched by closing the end-closure plate 7 of said end-cap.

The end-closure plate 7 is provided with a laterally bent wing 1' extending into the clearance-recess 30 as a closure therefor conforming in 65 shape with the curved wall of the end-cap. Preferably sufficient clearance is provided between the end-closure plate wing 1' and the edge of the recess 30, in the region of the lower end of the thread-guiding slit 31, to afford access to 70 said wing 1' for springing the end-closure plate 7 outwardly to release the nub 8 from the end-cap aperture 8.

It will be observed that the objects of providing for conveniently threading the bobbin-carrier 75 14 and for insuring against pinching of the bob-

bin-thread by closing the end-cap plate 7 have been attained by the present invention without sacrificing any portion of the work-arm surface essential to proper manipulation of the work in connection with stitching the same. The work is held against the work-support at the stitching point by a presser-foot 34 which, in the present case, is provided with a finger-guard 35.

Having thus set forth the nature of the invention, what I claim herein is:

1. In a sewing machine, a reciprocatory thread-carrying needle, a loop-taker complementary to said needle in the formation of stitches, a bobbin-carrier journaled in said loop-taker about which bobbin-carrier needle-thread loops are cast by said loop-taker, bobbin-thread tensioning means upon said bobbin-carrier, a thread-bobbin removably disposed in said bobbin-carrier, a frame structure disposed contiguous to said loop-taker, and thread-guiding means disposed upon said frame-structure with respect to said bobbin-carrier for directing thread drawn from said bobbin into position for effective engagement by said tensioning means.

2. In a sewing machine, a reciprocatory thread-carrying needle, a loop-taker complementary to said needle in the formation of stitches, a bobbin-carrier journaled in said loop-taker, means for restraining said bobbin-carrier against rotation with said loop-taker, bobbin-thread tensioning means upon said bobbin-carrier, a thread-bobbin removably disposed in said bobbin-carrier, and a work-arm housing said loop-taker and provided with a thread-guiding slit, said thread-guiding slit being disposed with respect to said bobbin-carrier for directing thread drawn from said bobbin into position for effective engagement by said tensioning means.

3. In a sewing machine, a reciprocatory thread-carrying needle, a work-arm free at one end thereof, a rotary loop-taker shaft within and extending lengthwise of said work-arm, a loop-taker carried by said shaft and embraced by the free end portion of said work-arm, a bobbin-carrier journaled in said loop-taker and restrained against rotation therewith, a bobbin-thread tension spring secured to said bobbin-carrier at the front side thereof, a thread-bobbin removably disposed in said bobbin-carrier, and thread-guiding means disposed at the front side of said work-arm and contiguous to said bobbin-carrier for directing thread drawn from said bobbin into position for effective engagement by said tension-spring.

4. In a sewing machine, a reciprocatory thread-carrying needle, a work-arm free at one end thereof, a rotary loop-taker shaft within and extending lengthwise of said work-arm, a loop-taker carried by said shaft at the free end of said work-arm, a cylindrical end-cap detachably secured upon said work-arm and open at the free end of said work-arm, a bobbin-carrier journaled in said loop-taker and restrained against rotation therewith, a bobbin-thread tension-spring secured upon the front side wall of said bobbin-carrier, a thread-bobbin removably disposed in said bobbin-carrier, and an openable end-closure plate for said end-cap, said end-cap having a thread-guiding slit in the front wall thereof contiguous to said bobbin-carrier and extending from the open end of said end-cap in a direction to guide thread drawn from said bobbin into position for effective engagement by said tension-spring.

5. In a sewing machine, a reciprocatory thread-

- carrying needle, a work-arm having an open free end and provided with a clearance recess extending into the front side wall of the work-arm from the open end thereof, a rotary loop-taker embraced by the free end portion of said work-arm, a bobbin-carrier journaled in said loop-taker and restrained against rotation therewith, said bobbin-carrier being provided in the front side wall thereof with a thread-slot open 5 at the rim of the bobbin-carrier, a bobbin-thread tension-spring secured upon the bobbin-carrier to overlie said thread-slot and bearing yieldingly against the bobbin-carrier wall above said thread-slot, a thread-bobbin removably disposed 10 in said bobbin-carrier, said work-arm having a thread-guiding slit extending upwardly from said clearance recess in a direction to guide thread drawn from said bobbin under said ten- 15 sion-spring, and an openable end-closure plate upon the free end of said work-arm and provided with a wing extending laterally from said plate into said clearance recess.
6. In a sewing machine, a reciprocatory thread-carrying needle, a work-arm free at one end and lengthwise disposed substantially normal to the path of needle-reciprocation, a loop-taker complementary to said needle and disposed within the free end portion of said work-arm, a bobbin-carrier journaled in said loop-taker and restrained against rotation therewith, a thread-bobbin removably disposed in said bobbin-carrier, 5 said work-arm having an open free end and a bobbin-thread receiving slit extending into said open free end, and an openable closure-plate for the open end of said work-arm.

HENRY C. NISSEN.
